LECTURE DESK

David Katz, Wilmington, Del.

Application February 26, 1938, Serial No. 192,755

12 Claims.

(Cl. 88—24)

This application is a continuation-in-part of my copending application Serial No. 155,390, filed July 24, 1937, and relates to certain novel lecture desks which are provided with means for displaying to the audience writing or sketches done by the lecturer during the course of his lecture.

More particularly, this invention deals with a novel lecture desk which enables the lecturer to illustrate his discussion with writing or sketches, without resort to the customary blackboard, which forces the lecturer to turn his face away from the audience. Briefly stated, my novel lecture desk contains in the top thereof a substantially horizontal panel of light-transmitting material, for instance a sheet of transparent glass over which is stretched a sheet of translucent or transparent paper, which serves as a writing plane for the lecturer. A light, suitably placed above the writing plane, casts a shadow into the interior of the desk of any figures written with opaque writing material on the writing plane; and this shadow is focussed, with suitable inversion and change of direction, by an optical system within the interior of the desk chamber, onto a projection screen placed in a substantially vertical position in a cut-away space in the rear wall of the desk, that is the wall normally facing the audience. The projection screen is made of shadow transmitting material, whereby the shadows focussed upon it from the inside of the desk show through to the outer face thereof, confronting the audience.

In the model described in my copending application, the writing panel consists of a flat sheet of translucent material. The latter may be either ground glass or a sheet of translucent paper; but in any event, the faces of the writing panel are two planes parallel to each other. The optical system, which consists of a convex lens and a plane mirror, or a system of lenses and mirrors, depends for its operation on the scattered light which reaches the lens from the various particles in the translucent writing medium.

Now, I find that the above system gives satisfactory results only where the source of illumination has a wide area compared to the aperture of the lens employed, as for instance where a number of electric lamps have their light reflected uniformly unto the writing plane by the aid of a reflector of large effective area. Such a system is practical with small models. With larger models, however, the required size of the reflector area tends to diminish considerably the practical adaptation of the device. On the

other hand, if the requisite illumination is permitted to come from a relatively small area, the projection on the screen is found to contain a bright spot in the middle of the screen area, with practically no illumination, and hence no shadow effects, in the surrounding regions. 5

It is accordingly an object of this invention to provide an improved lecture desk of the general type above indicated which will give satisfactory results even with a relatively concentrated source 10 of light. A further object of this invention is to provide an improved article of the above general type wherein the usable portion of the projection screen will be substantially uniformly illuminated throughout its expanse, with resultant good 15 light-and-shadow contrast, regardless of the shape or size of the illuminating means employed. A still further object of this invention is to improve the design of my lecture desk aforesaid whereby it may be made to give satisfactory results with less strong illumination than is required with my prior model, resulting not only in a saving of electric power but also in greater comfort to the lecturer in that he need not be exposed to the radiant heat from a large 20 cluster of lamps. 25

A still further object is to provide a design which lends itself more readily to modification for the production of large size models, than was my former design. Other and further important objects of this invention will appear as the description proceeds. 30

These and other useful objects are achieved by my present invention which consists, in general terms, of replacing the heretofore employed doubly plane writing panel by an optical member which is adapted to combine the functions of a writing plane with those of a light-condensing lens. In other words, the cut-away opening in the top of the desk, instead of being filled by a panel of glass which is plane on both sides, is according to my present invention, filled by a member of glassy material which is flat on the upper surface thereof and serves there as a writing plane, but is either shaped like a convex lens on the lower side or else combined with a condensing lens of any suitable form, whereby to bend light rays passing through it, into the general direction of the optical system below. 35 40 45

For a better understanding of my present invention, reference is to be made to the accompanying drawings which form an integral part of this specification. In these drawings—

Fig. 1 represents a vertical section of a lecture

desk built according to this invention, and employing a plano-convex lens as writing panel.

Fig. 2 represents a similar section through the foremost top portion of the desk in a modified form of this invention, employing an annular Fresnel lens.

Fig. 3 is a vertical section of a still further modified embodiment of my invention.

Fig. 4 is a perspective view, partly in section, 10 of the lens member employed as writing panel in the desk of Fig. 1, on a slightly enlarged scale.

Fig. 5 is an enlarged sectional view of the annular Fresnel lens employed as writing panel in Fig. 2.

15 Fig. 6 is an optical diagram, showing in simplified fashion one mode of disposition of the illuminating means, writing-panel lens, focussing lens and projection screen relative to each other.

20 Fig. 7 is a similar diagram showing a different mode of relative disposition.

Fig. 8 is a similar diagram showing a still different mode of disposition.

25 Fig. 9 is a similar diagram showing a modified form of disposing the illuminating means in any of the foregoing designs.

Fig. 10 is a simplified optical diagram showing the focussing of the points of shadow which come from the writing plane unto the projection screen.

30 Fig. 11 is a perspective view of a novel adaptation of my invention to the construction of large size models. The wall of the desk nearest the reader has been removed for the sake of exposing the interior. The inner partition has for the same reason been partly broken away.

Fig. 12 is a diagrammatic pictorialization of a modified form of the optical system to be employed in conjunction with the embodiment displayed in Fig. 11.

40 Fig. 13 is a similar, three-dimensional diagram of a still further modified form of the optical system.

Fig. 14 is an enlarged perspective view of the tilted-mirror system employed in Fig. 11.

45 Fig. 15 is a section either through line X-X or through line Y-Y in the writing panel of Fig. 11.

Referring now to Fig. 1 in detail—

1, 1 constitute the walls, top and floor of the 50 lecture desk which are made of opaque desk material, and are joined together to form an enclosed dark chamber, as in my former application. 2 is the writing panel, which will be described in detail later. 3 is the projection screen, 55 made of shadow transmitting material and supported pivotally at 31, with means for adjustment at 32. 4 is the focussing lens and 5 is the mirror of the optical system, both being supported on a suitable support 7 which is adjustable in position through screw 11 and slit 72 in the wall of the desk; finer adjustments of the 60 lens being obtainable by the aid of the threaded tube 42 for the lens, and axis 51 and set screw 52 for the mirror.

65 Under the eave of the desk on the side nearest the lecturer (or at any other convenient location) is a roll of light-transmitting paper 61, from which a sheet 6 stretches over the surface of the writing plane 2, and is held in tension by the 70 pivoted knife edge device 63 on one end and by the weight (or spring) 62 over the roll 61 at the other end. The desk is further provided on the interior with a partition 8, to prevent stray light from being scattered unto the projection screen; 75 the partition 8 is provided with an opening 81

at the bottom thereof to permit the principal beam of light to pass into the lens 4.

So far the novel lecture desk is substantially identical with the desk described in Fig. 2 of my copending application, Serial No. 155,390. The 5 slightly different mounting of the lens 4 and slightly different construction of the partition 8 are not inventive differences, being within the scope of my original invention above referred to. But the principal difference between the desk of 10 Fig. 1 of this application and the one of my copending application is in the nature of the writing panel 2.

Instead of being a flat pane of glass as in my 15 previous design, the writing panel in Fig. 1, here, is a plano-convex lens. One surface of it, more particularly the upper surface, is flat, as shown at 26 in Fig. 4, and forms the writing plane. The other surface, however, is convex, as at 27, and is of sufficient curvature to bend the light rays 20 coming from the illuminating means 15 into the general direction of the lens 4. Lenses of this type are known generally as "condensing" lenses. Precise focussing is not needed, and the location 25 of the focus may be either in advance of or beyond the lens 4.

The aperture of this lens, that is its width from edge to edge, may be anywhere from about 6 to 24 inches, depending on the size of writing 30 plane desired. Its outline may be circular, or it may be squared off, as at 21, 21 in Fig. 4. The material of the plano-convex writing panel may be glass or any suitable, hard, transparent material, for instance "Lucite" (a methyl-methacrylate resin). Or it may be compounded from two different materials, for instance glass and Lucite, crown glass and flint glass, as is customary in lens design. But the thickness of the glass should be kept down to a minimum, inasmuch as a thick lens is apt to distort the shadows on the 40 projection screen. For this reason, the radius of curvature, and consequently the focal length, of the condensing lens should be as large as possible.

The writing-panel lens may be lightly ground 45 on its flat surface, to be written on directly with a soft pencil or crayon. But it is preferable to have this lens clear throughout, and to use a sheet of transparent paper as the actual writing surface. On the other hand, extreme optical 50 perfection, such as freedom from aberration, is not essential to its performance in the present invention.

The lens is mounted in the top of the desk so 55 that its plane face 26 is flush with the top surface of the desk, to provide a continuous flat support for the writing paper. Since the width of the lens is for economical reasons kept down to a minimum, the writing is preferably done with 60 a lead pencil or sharpened crayon or ink, so that the figures and letters are relatively small. The optical system within the desk, and projection screen can be designed to effect any desirable degree of enlargement.

65 Cooperating with the plano-convex lens is a source of illumination 15, fixed at a definite distance above the writing plane by means of an adjustable support 11. This support may be independent of the desk or may be attached thereto, but to save the necessity of delicate adjustments in installation, the lamp support is preferably designed and built as a part of the desk. The lamp 15 is provided with a suitable reflector 70, preferably bearing at its end a condensing 75

lens 12, as explained more fully in conjunction with Fig. 9 below.

The mode of spacing the essential elements of the light projecting system relative to each other is shown diagrammatically in Figs. 6 to 9, inclusive, wherein the plane mirror 5 has been omitted for simplicity, inasmuch as it does not affect the principles of this discussion. Omission of the mirror enables us to represent the light rays travelling from the writing plane to the screen by straight lines, although in actual practice they are broken lines. It is to be remembered therefore that in actual practice the distance between the focussing lens 4 and the projection screen 3 is to be measured along the broken paths of the light rays instead of along the shortest path between the two. Figs. 6 to 9, together with Fig. 10, also bring out the quantitative relations involved, and aid one in selecting the proper dimensions and design data for any particular purpose.

In Figs. 6 to 10 inclusive, W represents the "writing plane", or condensing lens used as writing panel, as well as the diameter thereof. L represents the shadow focussing lens, as well as the diameter thereof. S represents the projection screen as well as the diameter thereof, assuming that the screen will be circular and just of the right diameter to accommodate the image projected from the field of W . In case W and S are rectangular or square, these letters may be considered as representing the length of their respective diagonals. O represents the source of illumination, for instance the lamp 15 in Fig. 1, or an arc light. It will be further assumed in these figures that f is the focal length of L , while F is the focal length of W .

Now, considering first Fig. 10, it will be observed that each opaque point in the writing plane W emanates a "beam of shadow" which is condensed by the focussing lens L and focussed upon the screen S as though it were a ray of light.

This focussing effect, and the position and size of the image, are utterly independent of the position or strength of the light source O , and are also independent of the focal length of the lens W . Consequently, the relations shown in Fig. 10 hold true with any of the modifications, as to mode of condensing the illumination, shown in Figs. 6 to 9, inclusive.

If S is of the correct dimensions to just accommodate the image of the entire field of W , then

$$\frac{S}{W} = \frac{P}{q} \quad (1)$$

p and q in turn are related to the focal length of lens L by the well known lens formula

$$\frac{1}{P} + \frac{1}{q} = \frac{1}{f} \quad (2)$$

From these formulas the requisite dimensions of W , S , p , and q , as well as the requisite focal length of L can be computed, if any three of these variables are assumed or determined by the practical requirements.

Referring now to Figs. 6 to 8, the focal length F of the writing panel W may be so chosen, and the light O may be located at such a distance, that the rays of light therefrom, after being bent by the lens W , come to a focus at a point in advance of L , as in Fig. 6; in the center of L , as in Fig. 7; or beyond L as in Fig. 8. Regardless where this point of focus is, and regardless indeed whether there is a sharp focus at all or merely a rough condensation of the light within a small region,

all the light that has passed through W will be just spread out over the area S (as defined by Formula 1), without loss, provided L is of sufficient width to intercept all these rays. This condition will be realized if

$$\frac{L}{S} = \frac{u}{p+u} \text{ or } \frac{L}{W} = \frac{q-y}{y} \quad (3)$$

in Fig. 6, and if

$$\frac{L}{S} = \frac{u}{p-u} \text{ or } \frac{L}{W} = \frac{y-q}{y} \quad (4)$$

in Fig. 8.

It is clear that any value for L which lies between those obtainable by Formulas (3) and (4) will be satisfactory. In all these cases S will be intensely and uniformly illuminated, since all the light from W is spread out upon S , without loss.

However, if the distances q and x be assumed as fixed, the layout of Fig. 6 will require W to have a shorter focus than in Figs. 7 and 8. The design of Fig. 8 will give the maximum focal length for any assumed value of L . A short focus implies a thick lens W , or else a limitation upon its aperture (diameter or diagonal). Neither of these is a desirable feature; therefore, the design of Fig. 8 is to be preferred.

From Equations (3) and (4), the following relations between y , q , L and W may be derived:

$$y = \frac{qW}{W+L} \quad (5)$$

in Fig. 6, and

$$y = \frac{qW}{W-L} \quad (6)$$

in Fig. 8.

The relation between y and x , in either case, is determined by the focal length F of the condensing lens W , by the simple lens formula:

$$\frac{1}{X} + \frac{1}{y} = \frac{1}{F} \quad (7)$$

This one when combined with (5) and (6) gives:

$$\frac{1}{x} = \frac{1}{F} - \frac{1}{q} \times \left(1 + \frac{L}{W} \right) \quad (8)$$

in Fig. 6, and

$$\frac{1}{x} = \frac{1}{F} - \frac{1}{q} \times \left(1 - \frac{L}{W} \right) \quad (9)$$

in Fig. 8. These formulas help select the proper dimensions for the various variables involved in the design of the desk, as more fully illustrated by the following discussion.

In practice, q will be limited by the height of the lecture desk to a value between about 2 to 3 feet, at the maximum. F cannot be greater than y , as determined by Formula (6). If F is to be equal to y , x in Formula (7) must be infinite. In other words, the writing plane should be illuminated by parallel rays of light. Formula (9) then becomes converted into

$$\frac{1}{F_{max}} = \frac{1}{q} \times \left(1 - \frac{L}{W} \right) \quad (10)$$

On the other hand, it is not practical to place the light too close to the writing plane, and, as already mentioned, it is not desirable to have a small F value for the lens W . Both of these factors suggest setting a lower limit to the value of x ; for instance, a value equal to that of y . In that event, F is just about $\frac{1}{2}y$. The most practical values of x will fall somewhere between these two extremes, which will locate the value of F somewhere between $\frac{1}{2}y$ and y .

75

To make F as near as possible to its upper limit, x must be larger than would be practicable according to Figs. 6, 7 and 8. Accordingly, the alternative arrangement of Fig. 9 is suggested. In this arrangement an auxiliary condensing lens C is provided, which is placed near the source of light as in the case of a search light. This lens not only concentrates the light from O upon the written plane, but also diminishes the angle of divergence of the light rays emanating from O , thereby producing an effect as though the lamp were placed at a much larger distance from W than it actually is. Mathematically speaking, lens C increases the value of x without bodily removing the lamp to an impractical distance. This modification also gives a sharper definition of image and a greater contrast between writing and background, rendering the projection more easily readable from a distance, even in daylight.

By placing O at the focus of C , the emergent light rays may be made actually parallel; ($x=\infty$). However, strictly parallel rays would require C to be of the same aperture as W , which is again objectionable from the viewpoint of cost. Therefore, in practice, some divergence is permitted, and x may be taken as having a value somewhere between y and $3y$. A specific illustration will make the discussion clearer.

Assume that q is to be 30 inches, and that the aperture of L is to be about $\frac{1}{3}$ that of W . Then, by Formula (10), the maximum operative value of F is 45 inches. This is also the value of y in Formula (6). If x be taken as $2y$, $x=90$ inches. Then, by Formula (9), the practical value of F is 30 inches.

The radius of curvature of a plano-convex lens is related to its focus by the formula

$$R=(n-1)F \quad (11)$$

wherein n is the index of refraction. Assuming a material for W whose index of refraction is 1.7 (flint glass), Formula (11) becomes $R=0.7 F$, whence, in our problem, $R=21$ inches.

Assuming now that it is not desirable to have the lens W more than 2 inches thick at its maximum, the permissible aperture of W is calculated readily by plane geometry. The formula is

$$W^2=8Rt-4t^2 \quad (12)$$

where t is the maximum thickness of the lens, and R is the radius of curvature. Applying this formula, $W=\text{about } 18$ inches.

Now, suppose that a magnification of $2\frac{1}{2}$ is desirable in the projection; then the required diameter of S is $2\frac{1}{2} \times 18 = 45$ inches. Of course, the actual screen may be larger than the found value, and may be rectangular, square, or any other shape, provided it accommodates the desired circle of projection.

The desired magnification value also determines the value of p at about 75 inches. The value of p in turn determines the length of the desk as measured from the lecturer's side to the audience's side, and further determines, jointly with the value of q , the focal length required of lens L . In practice, a stock size lens, approximating the determined focal length, will be selected for L ; and the value of p will then be adjusted to suit. In the instant case, Formula (2) suggests a lens of about 21 inches focal length, which in turn reduces the value of p , by the same formula, to 70 inches. Its aperture, from the previous assumption,

$$\frac{L}{W} = \frac{1}{3}$$

is to be about 6 inches. Here again, a larger width does no harm. Hence a 7 or 8 inch lens may be selected if desired.

In the same problem, if a threefold magnification is desired, a lens of 22.5" focus is required for L , and the screen should be not less than 54" on a side.

The value of x was assumed to be 90". A practical height for the illuminating means would be about 5 ft. above the writing plane, which would make it sufficiently high to clear by a comfortable margin the head of a tall person standing on a platform in front of the desk. Then, by plane geometry, the aperture of the lens C must be about 6 inches.

Of course, in lieu of a single element of light with a flash-light type lens in front of it, a fixture of considerable dimensions, employing several lamps may be used. In that case the impinging light rays may be made substantially parallel, with the result that F may be used to its full 45 inches. In that event, R is about 31.5"; permissible W , about 22"; when t is 2, and about 24.5" when $t=2.5$ ".

In the same problem, if crown glass or "Lucite" be selected as lens material for W , $n-1=\text{about } 0.5$. Then an aperture of 18" for W can be obtained only by increasing the thickness to 3 inches, which still is fairly reasonable. On the other hand if a 2-inch thickness is insisted on, W must be reduced to about 15 inches. A maximum thickness of $1\frac{1}{2}$ inches with crown glass will give a permissible aperture of about 13 inches.

In practice, it may sometimes be desirable to select a stock lens for W , and determine q and the other dimensions accordingly. For instance, a crown-glass, plano-convex condensing lens of 14" aperture and 21" focus is carried in stock by some manufacturers at this date. If it is desired to build a lecture desk according to this invention from this lens, y is first determined from Formula (7). Assuming that the lamp is placed at a distance of 5 feet and uses a condensing lens of 5" aperture, x is about 93 inches. Then y is about 27". Assuming now an aperture for L of 5", Equation (6) gives $q=\text{about } 17$ ". A threefold magnification would then require $p=51$ " and $S=42$ ". The requisite focal length of L would then be about 13".

In the same problem, if parallel light is employed ($x=\infty$), then $y=F=21$ ", $q=13.5$ ", $p=\text{about } 40$ ", $S=\text{about } 32$ ", and requisite $f=10$ ".

If in the same problem, the aperture of L is reduced to 4 inches, q becomes about 19", p about 57", and the requisite $f=14$ ". It is clear that all of the above designs lend themselves to practical use.

It was stated above that q is generally limited by the height of the table; this is due to the fact that the writing plane is substantially horizontal and that the lens 4 is substantially vertically beneath it. However, such an arrangement is not an absolute necessity. If desired, the mirror 5 may be placed in advance of the lens 4 instead of following it. Then the light rays will become broken into horizontal direction before they strike the lens, with the result that the latter can be placed at any point along the horizontal path of the rays. Consequently, the distance q can be increased to any desirable dimensions, with resultant beneficial effect upon the permissible value of F and consequent permissible width of W . This mode of disposition is therefore to be preferred where an extra large size of writing plane is desirable. The mirror in this

case, of course, should be made large enough to intercept all the rays of light descending from the writing plane. It is also clear that no mirror is then interposed between the focussing lens and the projection screen.

A different mode of increasing the size of the writing plane is illustrated in Fig. 2.

In this modification, the lens 2 is not an ordinary condensing lens, but what is known as an annular Fresnel lens. An enlarged section of such a lens is shown in Fig. 5. The ribs on the under surface of this lens run circularly around its center. The details of such a lens are well known, and need no detailed description. See, for instance, *Encyclopedia Britannica*, 14th ed., vol. 14, page 91. It is to be remembered, however, that because of the thick portions of the writing-panel lens tend to displace the image somewhat, and because the thickness of a Fresnel lens changes abruptly at its ribs, such a lens is apt to project upon the screen a series of concentric rainbow-colored rings, disrupting the continuity of the image. This undesirable effect can be weakened by using monochromatic light and by increasing the number of ribs, thereby decreasing their height differences at the points of abrupt change. In any event, the utility of this particular design is limited, and it is therefore not a preferred embodiment.

In Fig. 3 I have shown still a third modification of my invention, in which a double-convex lens is used in conjunction with an ordinary plane plate of glass to give the combined functions of the plano-convex lens of Fig. 1. The double-convex lens is placed underneath the writing plate, and as close to it as possible, as otherwise it is apt to distort the image somewhat. Of course, in lieu of a double-convex lens, a plano-convex lens with its flat face either upwards or downwards, or any other form of condensing lens, may be employed.

In a similar manner any other combination of lenses, prisms, etc., with a plane transparent surface may be employed, provided the combination produces the following two effects: (1) provide a flat support for the writing paper to be written on, and (2) bend the light rays coming from the illuminating source, into the general direction of the focussing lens 4.

It will be clear that in lieu of the simple focusing lens 4, a combination of 2 or 3 lenses in series may be employed, provided these are placed close to each other so as to effect altogether but one inversion of the image. Such compound lenses are quite common in the art of projection, and are designed to eliminate spherical and chromatic aberration. For all purposes of this invention such compound lenses are to be regarded as the equivalent of the lens 4 (or lens L) shown in the various figures and diagrams.

Turning now to Figs. 11 to 15 inclusive, these figures show several modifications of my invention whereby it is possible to increase the size of the writing-plane without resorting to costly condensing lenses of unusually large apertures. Instead, the writing panel may be composed of a plurality of smaller condensing lenses, placed edge-to-edge, with their plane faces uppermost, so as to pave out a continuous flat surface of large dimensions. In Figs. 11, 12 and 13, four such smaller lenses are employed.

The individual lenses 25, 25 are of course made of rectangular or square shape, with their edges trimmed down to straight lines, as shown in detail in Fig. 4, in order that each may fit in

properly with the other to form a continuous transparent plane. This is explained further by Fig. 15, which constitutes a section through the writing plane of Fig. 11, both along the line X-X, and along the line Y-Y.

In such an embodiment, four focussing lenses are required in lieu of the single lens 4 of Fig. 1, each of these focussing lenses 45, 45 cooperating with a corresponding condensing lens from the group 25, 25. Now, if a plane mirror were employed with this modification of my invention, the projection on the screen 3 would be scrambled, because the writing from quadrant A would be projected into quadrant D, that from B into quadrant C, etc. To prevent such disastrous results, the plane mirror 5 of Fig. 1 is replaced in Fig. 11 by a system of four mirrors 55, 55, which is shown more clearly in Fig. 14. The four mirrors are supported on a single plate 51, which is supported in inclined position in the same manner as mirror 5 in Fig. 1 so as to direct the shadow rays in the general direction of the screen 3. But each mirror on this support is lifted on its outer corner, for instance by the aid of adjusting screws 56, 56, and tilted inwardly 25 toward the center of the support. The tilt of each mirror is adjusted sufficiently to cause the shadow rays from quadrants A, B, C and D of the writing plane to be projected, respectively, into the correct quadrants A, B, C and D of the screen 3, and to cause these quadrants of projection to join up correctly at the edges without overlapping.

In this modification, the light source 15 is likewise replaced by a fixture of four individual light sources 155, 155, each cooperating with one of the quadrants A, B, C and D of the composite writing plane, and each provided with a reflector or condensing lens (not shown) designed to direct the light toward the center of the corresponding quadrant.

The paths of the rays of light and their cross reflection by the mirror system can be traced in Fig. 11 by following the central light rays a, b, c and d.

Apart from the features above described, the modification of Fig. 11 follows in general the design of Fig. 1, and may have all the details or variations of the latter. For instance, the projection screen may be inclined as in Fig. 1. Also, the mirrors 55 need not be supported on the same plate, but may be supported each with its respective lens 45 on an individual support, provided each mirror is placed at the correct angle to reflect the light into the corresponding quadrant of the projection screen. The mirrors may also precede the focussing lenses 45, 45, in which event the latter are placed substantially vertically, along the horizontal portion of the path of the rays of light, as already explained in connection with Fig. 1.

Fig. 12 is a modification of the embodiment shown in Fig. 11, in respect to the mirror system. Instead of four tilted mirrors, a plane mirror 5 is here employed, placed at an angle just as in Fig. 1. But after being reflected from the mirror, the light rays are refracted by means of a system of prisms 9 comprising four prisms 95, 95. Each of these prisms is bound by plane faces and tapers from the center of the system 9 toward one of its corners. In this fashion, the prisms refract the light rays a, b, c, d and direct them toward the quadrants A, B, C, D in correct order.

Fig. 13 is a further modification of the re-

flecting system of Fig. 11. Here, the mirror consists of two plane mirrors 56, 56, arranged in trough-like fashion on the common support 51, with the axis of the trough running transversely of the writing desk. Cooperating with this mirror is a prism system 9 consisting of two wedge-shaped prisms 96, 96 placed back to back, with their thin edges in a vertical direction. The action of this compound system on the light rays can be followed readily by tracing the lines *a*, *b*, *c*, *d* in this figure.

The modification of Figs. 11, 12 and 13 is adapted also to be used with a writing panel which is a flat sheet of glass, as in my parent application, instead of a system of condensing lenses. This modification, however, requires the lamps 155 to be spaced farther apart, so that each lamp is in line with the center of the corresponding quadrant on the writing plane and the corresponding focussing lens 45. Also, this modification, requires strong illumination coming from a source of wide area. It is therefore not a preferred modification.

It will be understood that the specific embodiments described above are merely illustrative and are not intended to limit the invention. Many variations in the details of construction may be made without departing from the spirit of this invention.

30 For instance, the lecture desk may have a floor built in therein, or may be made without a floor. The illuminating means may be a part of the desk, or may be omitted, to be installed locally in the auditorium with the installation of each unit. The partition 8 in any of the modifications may take any of the forms shown in the drawings of this application, or may be omitted altogether. Likewise, the projection screen 3 may be placed inwards of the front wall of the desk, as in Fig. 1, flush with it, as in Fig. 3, or may be moved out to the end of the hood 14 or other similar light-excluding extension built onto the desk.

Instead of a single lens and a single mirror in the optical system, any combination of lenses and mirrors may be employed which, in addition to focussing and projecting, will effect one net reversal of the horizontal dimension of the lecturer's writing and a net zero reversal of the top-to-bottom dimension thereof, thereby orienting the projected script on the screen in correct manner for reading by the audience. The projection screen may be made of fine cloth, ground glass, translucent paper, or any other material which will transmit shadows through itself while simultaneously scattering somewhat the light passing through itself. Many other variations and modifications will be apparent to those skilled in the art.

60 Again, the condensing lenses have been indicated above as made from the usual solid, glassy materials, such as glass or "Lucite". However, in view of their requisite large size, these lenses may, for the sake of economy, be built up from an outer glassy shell filled with a refractive liquid. For instance a large "watch glass" of spheroid curvature may be cemented around its periphery to a plane sheet of glass to form a plano-convex shell. A vent provided at a suitable point, communicating with a partially filled, sealed reservoir, may provide an outlet for thermal expansion and contraction of the liquid.

Of course, the liquid for such a purpose should be chosen of high boiling point, say over 80° C., low freezing point, say below 0° C. or below

-10° C., and convenient refractive index, say between 1.33 and 1.75. Water seems to satisfy these conditions to a fair degree. Other convenient liquids may be selected from physical and chemical tables. See, for instance, Handbook of Chemistry and Physics, 19th edition, pages 1526-1533 and 1533.

As for the sheet of paper 6 which is stretched over the writing panel 2, I find that the more transparent it is the better the contrast between writing and background on the projection screen. Best results are obtained with highly transparent artificial cellulosic sheeting, for instance non-moistureproof "Cellophane".

I claim as my invention:

1. An apparatus for projecting handwriting, comprising in a single unit of furniture a substantially horizontal writing panel adapted to support a sheet of light-transmitting writing material on the upper surface thereof, a substantially vertical projection screen, and a focussing system; said writing panel being composed of light-transmitting material and being provided on the underside and adjacent thereto with light-condensing means, thereby being adapted to condense and to pass through itself into the space beneath itself light rays coming from a source of illumination above said writing panel through said writing material; said focussing system being disposed between said writing panel and said projection screen and being adapted to project upon the latter the light rays which come from the former, and to focus upon said screen shadows of any writing or figures done on said writing material with a light-absorbing writing medium; and said screen being composed of shadow transmitting material whereby to transmit said projected light and focussed shadows through itself to the other face thereof, thereby displaying the writing or figures as shadows upon an illuminated background; said writing panel, focussing system and projection screen being held together in their proper relative positions by said single unit of furniture, and the latter being shaped and proportioned to serve simultaneously as a lecture desk, and to form a substantially enclosed space behind said projection screen, thereby excluding stray light from the inner face of the projection screen; said writing panel being located in the top of said furniture unit, in convenient position for writing thereon by a lecturer during the course of his lecture while facing the audience; said projection screen being disposed to display the projection to the audience while the latter is facing the lecturer; and said furniture unit being free of any obstructions or members in the line of sight between the lecturer and his audience.

2. An apparatus for projecting handwriting, comprising in a single unit of furniture a substantially horizontal writing panel supporting a sheet of light-transmitting writing material stretched over the upper surface thereof, a substantially vertical projection screen, and a focussing system; said writing panel consisting of a plano-convex lens of transparent material, thereby being adapted to condense and pass through itself into the space beneath itself light rays coming through said writing material from a source of illumination above said writing panel; said focussing system comprising a focussing lens and at least one plane mirror cooperating with each other to project upon the projection screen the light rays coming through the writing panel while simultaneously focussing upon said screen shad-

- ows of any writing or figures done on said writing material by the aid of a light-occluding writing medium; and said screen being composed of shadow transmitting material, whereby to transmit said projected light and focussed shadows to the other face thereof, thereby displaying the writing or figures as shadows upon an illuminated background, said writing panel, focussing system and projection screen being held together in their proper relative positions by said single unit of furniture, and the latter being shaped and proportioned to serve simultaneously as a lecture desk, and to form a substantially inclosed space behind said projection screen, thereby excluding 10 stray light from the inner face of the projection screen; said plano-convex writing panel being disposed in an opening in the top of said furniture unit with its plane surface uppermost, in convenient position for writing thereon by a lecturer during 15 the course of his lecture while facing the audience; and said projection screen being disposed in said furniture unit with its outer face displayed to the audience while the latter is facing the lecturer.
- 20 3. An apparatus as in claim 2 in combination with means of illumination located outside said furniture unit above said writing panel, said illuminating means comprising a source of light and a condensing lens, whereby to throw upon said writing panel a concentrated beam of light.
- 25 4. A combination as in claim 1, the writing panel being formed by a plane sheet of glass associated with a converging lens located immediately beneath the same within the interior of 30 the cabinet, whereby to converge the light passing through said writing panel into the interior of the cabinet.
- 35 5. A lecture desk comprising in a combination a cabinet, a writing panel in the top of the cabinet consisting of light-transmitting material, a shadow receiving screen in one of the vertical sides of the cabinet composed of shadow transmitting material, an optical system within the cabinet adapted to intercept shadows coming 40 from the writing panel and to project them upon the screen, said optical system being composed of a plurality of focussing lenses, each of which is adapted to receive light rays and shadows from a separate region in the writing panel, and each 45 being associated with independently adjustable means for breaking the light rays passing through said focussing lens and for directing them upon a definite and separate region on the projection screen, corresponding in orientation 50 to the region on the writing panel where such rays originated, the said separate regions and orientations being so selected with respect to each other that the separate projections by the various focussing lenses upon said screen add up on said 55 screen and present to view an orderly and continuous projection of the entire field of writing laid out on the writing panel.
- 60 6. A lecture desk as in claim 5, the writing panel being composed of a plurality of plano-convex lenses fitted edge to edge to form by their plane surfaces a continuous writing plane, each of said plano-convex lenses acting to 65 condense light rays passing through itself and to direct it toward the corresponding focussing lens cooperating therewith.
7. An article of lecture-room furniture comprising a desk having a top member and wall members of opaque material forming a substantially enclosed, darkened chamber; said top member having at least a portion thereof removed and replaced by a writing panel composed of light transmitting material; and one of the wall members having likewise a portion thereof removed and covered up by a shadow transmitting screen positioned to display to an audience facing said desk light and shadows impinging upon said screen from within said chamber; said writing panel being adapted to cooperate with means of illumination external to the desk whereby to transmit into the interior of the darkened chamber light coming from said illumination means and to transmit shadows of figures written on the writing plane with light-absorbing writing material; and an optical projection system within the interior of said desk placed below 10 said writing panel in substantial alignment with the light rays coming from said writing panel, said optical projection system including image-forming means and image-reversing means co-operating with each other to focus upon the inner 15 side of the projection screen an image of shadows coming down from the writing panel and to reverse such image in the horizontal dimension, whereby such image when transmitted through the screen material to the outer surface 20 thereof shall appear to an audience facing the projection screen to have the same up-and-down and right-and-left orientation as the original figures on the writing panel have from the viewpoint of the lecturer.
- 25 8. An article of lecture-room furniture as in claim 7, having further means, including a light-converging lens, associated with said writing panel whereby to concentrate the light-rays coming through the writing panel and to bring them 30 substantially to a focus at a region within the interior of said chamber in the vicinity of said optical projection system.
- 35 9. An article of lecture-room furniture as in claim 7, said writing panel consisting of a plano-convex lens having its plane surface substantially 40 flush with the top surface of said desk, thereby to serve as a writing plane.
- 45 10. An article of lecture-room furniture as in claim 7, having further means associated therewith whereby to stretch a sheet of light-transmitting paper over said writing panel, thereby to serve as writing paper.
- 50 11. An article of lecture-room furniture as in claim 7, said writing panel consisting of a plano-convex lens having its plane surface substantially 55 flush with the top surface of said desk thereby to serve as a writing plane, and said desk having further means associated therewith whereby to stretch a sheet of transparent paper 60 over said plane surface of said writing panel thereby to serve as writing paper.
- 65 12. An article of lecture-room furniture as in claim 7 having further means associated therewith whereby to direct a concentrated beam of light from a light source above the top of the desk unto said writing panel and through it into the interior of the desk in the direction of said optical projection system.
